UNITED STATES PATENT OFFICE.

JOHN BONNER SEMPLE, OF SEWICKLEY, PENNSYLVANIA.

INDICATING THE TRAJECTORY OF PROJECTILES.

809,988.

Specification of Letters Patent.

Patented Jan. 16, 1900.

Application filed June 22, 1905. Serial No. 286,442.

To all whom it may concern:

Be it known that I, JOHN BONNER SEMPLE, a citizen of the United States, residing at Sewickley, in the county of Allegheny and State of Pennsylvania, have invented or discovered certain new and useful Improvements in Indicating the Trajectory of Projectiles, of which improvements the following is a specification.

10 The invention described herein has for its object the causing of the continuous flow of a material from a projectile during its flight, thereby rendering it possible to constantly follow the projectile with the eye while passing from the gun to object aimed at.

15 In general terms, the invention consists in applying pressure to a suitable material carried by the projectile to cause flow from the containing-chamber during the flight of the 20 projectile.

The invention is hereinafter more fully described and claimed.

25 In the accompanying drawings, forming a part of this specification, Figure 1 is a sectional view of a projectile embodying my improvement and also showing a portion of a rifled gun-barrel. Figs. 2 to 7 are similar views illustrating modifications of my improvement, and Fig. 8 is an end view of the 30 projectile shown in Fig. 6.

35 In the practice of my invention suitable material is placed in a chamber formed in or carried by the projectile. The material used will depend upon whether the projectile is used in daylight or at night. For a daylight tracer I have found that a finely-commинuted substance, as lampblack, either alone or mingled with oil or water, will form an effective halo, while for night I employ a substance 40 which will ignite on exposure to the atmosphere—as, for example, zinc ethyl or a solution of phosphorus in carbon bisulfid, which will ignite and burn on exposure to the atmosphere. As the combustion of these substances will produce both light and smoke, they can be used both at night and in daylight.

45 The material employed may be placed, as stated, in a chamber formed in the projectile, as the cavity usually charged with an explosive, as shown in Figs. 1, 2, 4, and 5, or in a chamber formed in a block 2, carried by the projectile. It is preferred that the block 2 should be constructed and arranged to close 55 the chamber for the explosive charge, taking

the place of the usual base-plug and carrying the fuse 3 for igniting the explosive charge.

In the construction shown in Figs. 1, 2, and 3 the expansive force of gases generated by the propelling charge is employed for forcing the material from the containing-chamber. In the construction shown in Fig. 1 a tube 4, bent so that the end within the cavity will be adjacent to the side of the cavity, is held in position by a plug 5, screwing into the main base-plug 6. The plug 5 serves to close the opening through which the material is charged in the chamber. In order to prevent any accidental escape of the tracing material, a temporary stopper adapted to be forced out by the pressure of the gases of the propelling charge is placed in one end of the tube 4. The chamber is not completely filled with the material, but room left for the formation of an open space, with walls formed of the material, as will be hereinafter explained. On the combustion of the propelling charge a portion of the gases under high pressure will enter the chamber. While the projectile is within the gun the pressure of the gases in the latter will prevent any escape of gases from the chamber. During the movement of the projectile along the gun the former will be subjected to a high rotary motion, and as the material in the cavity is of greater specific gravity than the gases the material will move outwardly and be evenly distributed on the walls of the chamber, displacing the gases from around the inner end of the tube 4 and cause them to segregate in the form of a bubble around the axis of rotation of the projectile. When the projectile passes beyond the influence of the propelling gases, the expansion of the gases in the chamber will force the material out through the tube 4, producing a plainly-visible halo or comet-like tail at the end of the projectile.

In lieu of the tube 4 a passage 7 may be formed through the plug 6, near the periphery of the latter, as shown in Figs. 2 and 3, so that gases cannot escape through the passage until practically all the material has been driven out. In this construction, as in that shown in Fig. 1, the gases entering on the combustion of the propelling charge are segregated around the axis of rotation of the projectile. When the projectile is loaded with a bursting charge, the chamber for the tracer material is formed in the base-plug 2, as heretofore stated. Provision is made for the entrance

of the gases and the expulsion of the tracer material either as shown in Fig. 1 or as shown in Figs. 2 and 3.

In lieu of utilizing the gases from the combustion of the propelling charge provision can be made for setting up a chemical action in the chamber, whereby a sufficient pressure is produced to expel the tracer material. The chemical elements employed are so arranged in the chamber as to be normally inoperative, but capable of being brought into operative relation on the explosion of the propelling charge or the movement of the projectile. In the construction shown in Fig. 4 I employ a combustible material, which is arranged in a tube 8, arranged within a cylinder 9, secured to the base-plug 6, closing the chamber in the projectile. The cylinder is longer than the tube, which is normally held in a forward position by a suitable means, as a frangible pin 10. On the forward movement of the projectile the pin will be sheared or broken, allowing the firing-pin 11 to contact with a cap 12, whereby the charge in the tube is ignited. By the expansion of the gases of the charge the end of the cylinder is forced open, allowing the gases to escape into the chamber of the projectile and by expansion therein force the tracer material out through the passage 7. The rapid rotation of the projectile will cause the heavier tracer material to move outward and the gases to segregate around the axis of rotation of the projectile, and as the outlet-passage is eccentric to the axis of rotation the gases will not escape until all or nearly all the tracer material has been forced out. The passage 7 is closed to prevent the material from escaping except when pressure is generated in the chamber and to prevent the entrance of gases from the propelling charge.

charge.

The expelling pressure may be applied to the tracer material by mechanical means, a convenient construction to that end being shown in Fig. 5. A piston 13, arranged within the chamber, is adapted to be forced toward the outlet-passage 14 by a spring 15, which is placed under compression at the time of charging the material into the cavity.

45 It is preferred that the piston and spring should not become operative until the projectile has begun its movement, and to this end I employ a suitable lock, which may consist of spring-fingers 16, engaging the piston and connected to a stem 18, secured to the projectile. As the projectile revolves in its flight the fingers will be disengaged from the piston by centrifugal action, permitting the spring to shift the piston. The material is

55 retained in the chamber by a cork or stopper in the passage 14, which is displaced by the pressure of gases from the propelling charge. As soon as the projectile passes beyond the action of the propelling gases the piston will

60 be released by centrifugal action and the

65

spring will operate to shift the piston and cause a steady flow of material from the chamber.

The high velocity of rotation of the projectile can be utilized to effect the expulsion of the tracer material. In the construction shown in Fig. 6 a bent tube 19 is so supported by a plug 5 in the main base-plug 6 that its inner end will be closely adjacent to the side of the chamber. The outer portion of this tube extends out radially along the rear face of the projectile, so that its end or discharge-orifice is a greater distance from the axis of rotation than the inlet-orifice of the tube. In the construction shown the tube 19 is made in two sections screwing into opposite ends of the plug 5. In order to provide a contracted throat, the holes into which the tube-sections are inserted are separated by a diaphragm 21, through which is formed a passage smaller than the internal dimensions of the tube. The centrifugal force generated by the rotation of the projectile will exert a considerable outward pressure on the material and cause it to flow into the tube, and as the discharge-orifice is farther from the axis of rotation than the inlet a siphoning action will be set up to cause the material to flow through the tube.

As the projectile may not attain a sufficient velocity of rotation to effect the discharge of the material until after it has traveled a considerable distance and as it is frequently desired to follow the projectile from the muzzle of the gun, provision is made to effect a discharge of the material as soon as the projectile is relieved of the pressure of the propelling gases. To this end the inlet-orifice α of the tube 19 opens in the direction of rotation of the projectile, so that as soon as the projectile begins to rotate tracer material will be forced into the tube. This action is due to the fact that the material will not immediately follow the rotary movement of the projectile, and hence the tube will be forced through the material and a portion thereof scooped up and forced through the tube.

When the chamber is formed in the base-plug 6, as shown in Fig. 7, a radial discharge-passage 20 may be formed through the wall of the chamber. In such case the discharge of the tracer material will be due to centrifugal action. In order to prevent a crushing of the walls of the chamber by the pressure of the propelling gases, a rather large opening 18 is formed for the admission of the gases, so that such gases may quickly enter and escape as soon as the projectile passes from the gun.

It is characteristic of my improvement that the flow of the material is due to the application of an expansive force to the material during the flight of the projectile, and under the term "expansive" is included the ac- 130

tion of the compressed gases, the action of a spring, and the force derived from the rotation of the projectile.

I claim herein as my invention—

5 1. As an improvement in the art of indicating the trajectory of projectiles the method herein described, which consists in charging the projectile with a suitable material and causing a discharge of the material into 10 the atmosphere by pressure applied from a source independent of said material during the flight of the projectile.

15 2. As an improvement in the art of indicating the trajectory of projectiles, the method herein described which consists in charging the projectile with a suitable material and a discharge of the material by applying thereto an expansive force from a source independent of said material during the flight 20 of the projectile.

25 3. As an improvement in the art of indicating the trajectory of projectiles the method herein described, which consists in charg-

ing the projectile with a suitable material and causing a discharge of the material by 25 subjecting it to centrifugal action during the flight of the projectile.

4. As an improvement in the art of indicating the trajectory of projectiles, the method herein described which consists in charging the projectile with a suitable material and causing a discharge of the material by 30 a siphoning action.

35 5. As an improvement in the art of indicating the trajectory of projectiles, the method herein described which consists in charging a material into the projectile and causing the material to flow from the projectile by rotating the latter independent of the material.

In testimony whereof I have hereunto set 4 my hand.

JOHN BONNER SEMPLE.
